UNITED STATES PATENT OFFICE.

NOBLE M. PATRICK AND PLEASANT W. HORN, OF CHARLOTTE, NORTH CAROLINA.

VALVE MECHANISM FOR DISPENSING FLUIDS.

Application filed April 28, 1926. Serial No. 105,186.

Our invention relates to improvements in valves, and more especially to valves adapted to be placed on the end of a hose through which fluids are desired to be passed for dispensing into containers.

It is a matter of common knowledge that it is an every day occurrence at filling stations for filling the tanks of automobiles that the hose and nozzle is withdrawn from the tank before all the gasoline has run from the same into the tank, thus spilling the gasoline over the tank and over parts of the automobile, thus increasing the fire hazards. It is an object of our invention to make such occurrences impossible.

In the patent to Patrick, Number 1,549-500, dated August 11, 1925, means are provided for partially effecting the desired result. This patent issued to the applicants, and this invention relates to means for more perfectly obtaining the desired result.

In the above-referred to patent the pressure is directly against the head of the valve, and it is an object of this invention, to cause the liquid to press against the side of the valve, thus causing it to operate more easily and effectively.

Another object of our invention is to provide a valve adapted to be attached to the end of the hose used with the ordinary gasoline filling pump at gasoline filling stations, wherein the weight of the hose and the gasoline contained therein will automatically open the valve when our device engages the portions of the tank on the automobile around the orifice for filling said tank.

Another object of our invention is to provide simple means to be attached to the end of the hose in a gasoline pump at a filling station which will enable the operator to control the flow of gasoline without being in close proximity to the pump, and at the same time making it impossible to spill gasoline around the tank.

Another object of our invention is to provide fluid dispensing means in which the fluid enters the dispensing means at an angle to its longitudinal axis, thus holding the device in position in the orifice of the con-

tainer into which the fluid is desired to be dispensed.

Having thus stated some of the objects of our invention, a brief description of one embodiment of our invention is set forth in the accompanying drawings, in which—

Figure 1 is a side elevation of our valve, showing in dotted lines the valve and associated parts in raised position;

Figure 2 is a longitudinal sectional view taken along the line 2—2 in Figure 1, looking in the direction indicated by the arrows;

Figure 3 is a cross-sectional view of our valve taken along the line 3—3 in Figure 2, looking in the direction indicated by the arrows;

Figure 4 is a cross-sectional view taken along the line 4—4 in Figure 2, looking in the direction indicated by the arrows.

A brief description of the drawings having been given, a detailed description will now follow in which the numeral 10 indicates the tubular section which has a spider member 11 in its upper interior portion, which spider member is integral with the wall portions thereof. This spider member 11 has a perforation 12 in its central portion. On oppositely arranged portions of the walls of the tubular section 10 there are the longitudinal slots 13 and 14 in which the pin 15 slides in an up and down manner. A valve 16 is seated in the upper end of the tubular member 10, and said valve has a stem 16' which passes through the perforation 12 and extends downwardly inside of the tubular member 10 and has a hole 85 through its lower end through which the pin 15 passes. A compression spring 17 is coiled around the valve stem 16' and is held at its ends by the spider 11 and the pin 15.

Loosely and slidably encircling the tubular section 10 is an annular member 18 which has a circular projection 19 around its upper portion. This annular member 18 has interiorly threaded holes through its wall portions for the reception of the pin 15, said pin having threads on its ends for engagement with the threads in these holes.

The upper end of the tubular member 10,

has exterior threads 20 thereon, which are adapted to receive the lower interiorly threaded end or base of the hollow member 21. This member 21 is of approximate Y-shape, and has one of its prongs or branches closed at its end. The other branch 22 of this Y-shaped member 21 has an enlarged open end which has interior threads 23 therein which are adapted to receive the threaded end of the hose member 24. This hose 24 is of the type used at gasoline filling stations for conducting the gasoline from the pump to the tank of an automobile.

It will be noted in observing the dotted lines in Figure 1 that the upper end of the tubular member 10 with the valve 16 projects above the junction point of said tubular member and the open branch of the Y-member, so that while the valve is closed all of the pressure of the gasoline is not directly on top of the valve, and when the valve is in the open position shown by the dotted lines in Figure 1 there will be practically no pressure on the top of the valve, and therefore there will be no tendency on the part of the valve to close while the gasoline is passing therethrough until the pressure on the projection 19 is relieved.

It will be understood that our device is not to be limited in use to dispensing gasoline at filling stations, but may be used in connection with any means for controlling the dispensing of fluids.

It will also be understood that the shape of our device is an important feature, as this causes the device to remain in an orifice notwithstanding the pressure exerted by the column of fluid in the fluid conducting means.

The method of operation is as follows:

By means of the threads 23 the valve is attached to the hose of a gasoline filling tank, said hose being indicated by the reference numeral 24. The tubular member 10 is inserted in the opening in the tank on the automobile and the projection 19 will engage the tank on the automobile and the weight of the device together with the weight of the gasoline in the hose 24 will press the annular member upwardly and will thus open the valve 16 and the gasoline will flow through the valve into the gasoline tank of the automobile until the valve is lifted out of the tank on the automobile, when the valve will automatically close on account of the pressure on the projection 19 being relieved.

It is thus seen that we have devised efficient means for the controlling of the dispensing of gasoline and other fluids in such a manner as to prevent spilling the same while dispensing.

Having thus described one illustrative embodiment of our invention, we desire it to be understood that although specific terms

are employed, they are used in a generic and descriptive sense and not for purposes of limitation, the scope of the invention being set forth in the appended claims.

Claims:

1. Dispensing controlling means comprising a tubular member, a valve adapted to be seated in the upper end of the tubular member, a downwardly projecting stem for said valve, a guideway for said valve stem, a hole through the lower end of the valve stem, slots in the wall portion of the tubular member, an annular member slidably mounted on the exterior surface of the tubular member, a pin passing through the annular member, said slots and the hole in the lower portion of the valve stem, a coiled spring mounted around the valve stem between the pin and the guideway, an approximately Y-shaped member having the end of one of its branches closed and having its base portion threadedly secured to the exterior surface of the tubular member, the other branch of the approximately Y-shaped member being adapted to be secured to a source of fluid supply, all of said parts being adapted to cooperate to open the valve when pressure is applied to the annular member.

2. In a valve, an approximately Y-shaped hollow member, a valve and valve stem mounted in the lower portion of said member and having its seat above the junction point of the lower portion with its branches, sliding means on the Y-shaped member adapted to actuate the stem to open the valve when a pre-determined amount of pressure is applied to said sliding means, a spider member having a hole therein serving as a guideway for the valve stem, and a coiled spring for closing the valve mounted around the valve stem below the valve.

3. In a valve adapted to be connected to the end of a fluid conductor, a tubular member, a valve mounted in the tubular member, a spider in the tubular member having a hole in which the stem for the valve is adapted to slide, a forked fluid containing chamber secured to the end of the tubular member, sliding means mounted on the tubular member and being connected to the valve stem for operating the same, a coiled spring mounted around the valve stem, between the means for connecting the valve stem to the sliding means and the spider member, one of the branches of said forked fluid containing chamber adapted to be connected with a source of fluid supply, said branch forming an angle with a line drawn through the longitudinal center of the valve.

4. In a valve mechanism adapted to be used for dispensing fluids, a straight tubular portion, a valve and valve stem, a fluid containing chamber connected to one end of the tubular portion, a valve in said chamber having a stem extending into said tubular

portion, an intake portion integral with the fluid containing chamber, through which a fluid is adapted to flow and approach said valve at an angle to its longitudinal axis, a 5 spider member in the said tubular member having a hole adapted to receive the valve stem, a coiled spring mounted around the valve stem below the spider member and normally closing the valve, and an annular member slidably mounted on the tubular 10 portion and connected to the valve stem.

In testimony whereof we have signed this specification.

NOBLE M. PATRICK.
PLEASANT W. HORN.
